F. B. Brock,

UNITED STATES PATENT OFFICE.

FENELON B. BROCK, OF WASHINGTON, DISTRICT OF COLUMBIA.

CIGAR-CUTTER.

SPECIFICATION forming part of Letters Patent No. 373,436, dated November 22, 1887.

Application filed February 12, 1887. Serial No. 227,400. (No model.)

To all whom it may concern:

Be it known that I, FENELON B. BROCK, of Washington, in the District of Columbia, have invented an Improvement in Cigar-Cutters, of which the following is a specification, reference being had to the accompanying drawings, and to the reference-letters thereon, which form a part of this specification.

My invention relates to a cigar-cutter having a dice-throwing attachment.

Figure 1 is a perspective view of the invention. Fig. 2 is a vertical section thereof. Fig. 3 is a horizontal section with the base removed. Fig. 4 is a vertical section of a modification of the invention. Fig. 5 is a horizontal section thereof with the base removed.

Various departures may be made from the construction shown by the above figures without departing from the spirit of my invention as set forth by the claim.

a represents a box or receptacle.

b is the base of the box.

c represents an opening in the box.

d is a vibrating diaphragm forming the bottom of the opening c.

e is a lever pivoted at f. g is the handle of the lever.

h is a hammer or stud carried by the lever.

i is a spring for normally throwing the lever e upwardly and the hammer h against the diaphragm d.

k are holes for the insertion of the tip ends of cigars.

l are lateral arms extending out from the lever e.

m are knives carried by the arms l of lever e and arranged to pass across the openings or holes k.

n is a bell-glass arranged to cover the opening c and diaphragm d, and is made removable. The box a may, however, extend above the diaphragm and be provided with a glass top.

o are dice or other light articles, which are placed upon the diaphragm within the bell-glass n.

p is a cover arranged to close the opening s, through which the cigar-clippings are removed.

Figs. 4 and 5 show a modification of the cigar-cutter, in which the hammer h is carried by a lever independent of that which carries the knives m, and has the handle g.

t is the lever carrying the hammer h. It is pivoted at j. u is a spring for throwing lever t upwardly.

v is a pin or stud on lever t.

w is a pawl or dog on lever e. x is a pin on said lever, limiting the movement of the dog. The dog is pivoted at y.

The operation of the cutter, as shown in Figs. 2 and 3, is as follows: Depress the handle g, having previously inserted the end of a cigar in one of the holes k. The knives m will clip the end of the cigar as the lever is pushed down. Then release the handle and lever and the spring i will throw the lever and its hammer h against the diaphragm d, causing the latter to vibrate and throw the dice up into the bell-glass n.

In Figs. 4 and 5 the lever e is depressed until the dog w rides off the pin v, when the spring u will throw the hammer against the diaphragm. When the lever e is released, the dog strikes the pin v and is partially rotated thereby, so that it passes above the pin v, when the weighted end of the dog will restore it to its normal position. The pin x prevents the dog from rotating the other way, and holds it in engagement with pin v until it rides off therefrom.

I claim—

A cigar-tip cutter and dice-thrower consisting of a casing having an opening or openings for the reception of the tips of cigars and a flexible cover or diaphragm, said casing carrying a glass or guard, in combination with a projecting hand-lever pivoted to the casing, a cutting edge, and a hammer, substantially as set forth.

In testimony whereof I affix my signature in presence of two witnesses.

F. B. BROCK.

Witnesses:

FRANK BRAWNER,
M. L. WILLIAMS.
